UNITED STATES PATENT OFFICE.

ERNST FREY, OF TROISDORF, NEAR COLOGNE-ON-THE-RHINE, GERMANY.

FUEL-INJECTION DEVICE FOR DIESEL MOTORS WITHOUT COMPRESSORS.

Application filed March 7, 1924. Serial No. 697,653.

To all whom it may concern:

Be it known that I, ERNST FREY, a citizen of the German Republic, and resident of Troisdorf, near Cologne-on-the-Rhine, Germany, have invented a new and useful Improved Fuel-Injection Device for Diesel Motors Without Compressors, of which the following is a specification.

My invention relates to a fuel-injection device for use in connection with Diesel-motors; more especially it relates to a regulable injection pump for use in connection with Diesel-motors without a compressor, this pump being driven by a cam, as well as by a spring, as is fully described hereinafter.

The suction-valve of the pump operates in known manner as return-flow valve. The stroke of the plunger of the pump can be varied in such a manner by means of a shift-able intermediate lever arranged between the driving cam and the plunger that, on one side, the plunger can enter more or less deeply into the pump chamber, although the total stroke remains approximately equal, and that, in spite thereof, on the other hand, the plunger reaches through a certain height always at the same point in the engine cycle.

The feed-pump is distinguished from similar ones by the feature that the same motion is transmitted to the suction valve, which can be adjusted in such a manner that during the suction stroke it touches the seat provided for it always at that position of the plunger which this latter passes in the same point of time at all loads.

My invention is illustrated by way of example in the accompanying drawing in which Figure 1 is a longitudinal section through an arrangement and combination of parts according to my invention, and Figure 2 is a modification thereof.

Referring to Figure 1, the shaft 2 is supported in the casing 1 and carries the plunger-actuating cam 3 which acts on the guide-member 4 of the plunger 5. The guide-member 4 is subjected to the pressure of a spring 6 housed therein, and the plunger performs its suction stroke under the pressure of this spring. Between the cam 3 and the guide-member 4 is inserted a regulating intermediate arm or lever 8 which is hinged at 9 to a slide 24 that can be shifted inwards or outwards by means of an arm or lever 25 secured to a shaft 26.

The suction-valve 10 is subjected to the pressure of a spring 11 which always tends

to close it; it is opened during the suction period firstly by means of a lever or arm 17 supported at 18 in the casing 1 of the device and engaging with its free end a recess 4^a in the guide-member 4; secondly by a lever or arm 14 supported at 15 on the top of the casing and provided with an adjustable transmission screw 13 which depresses the valve stem 10' and opens, thus, the valve 10; and thirdly by a rod 16 connecting the lever or arm 17 with the lever or arm 14, as shown.

The liquid fuel enters into the pump casing through the aperture 12 and flows between the opened valve 10 and its seat down into the pump chamber 1'.

When the valve 10 has been closed by the spring 11 owing to the arm or lever 14 having been lifted by the guide member 4 which has been lifted, in its turn, by the cam 3, the liquid fuel is forced out of the pump chamber 1' by the plunger 5 which is moved upwards together with said guide-member 4. The fuel leaves the chamber 1' through a channel 19 and enters into an annular or cylindrical chamber 20' enclosing a valve 20 which serves as both the pressure valve and the injection valve of the pump. This valve is kept closed by a spring 21 enclosed in the body thereof, as shown, and this latter is pressed inwards and the spring is correspondingly compressed by the pressure of the fuel on the annular surface between the larger and the smaller diameter of said valve. The fuel then escapes at 23^a into the cylinder. The upper arm 1^c which forms a lateral extension of the standard or column 1^b of the casing 1 is connected with a suitably located flange of the cylinder by means of the flange 23 and a plurality of bolts (not shown).

The stroke of the valve 20 is generally only very short and is limited by an abutment member 22 which is inserted into the inner end of the bore containing said valve. The spring 21 is enclosed in cavities of the valve body and of said member 22, as shown.

The slide 24 which has already been mentioned above is located in a lateral extension 1^a of the casing 1, and the extent of its movement is limited in either direction by a screw 27, the inner end of which engages a recess 24' of said slide. One of the end-positions of the slide 24 means "full load," the other "standstill."

The manner of operation of the pump is as follows:

The position of the slide 24 as shown is that for full load, and the upper movable parts of the device are in the position in which the injection will just commence. The cam 3 is rotating in the direction indicated by the arrow (left hand from it), and the suction valve 10 has just been seated on its seat in the head of the casing. Supposing the cam 3 is now moving through the angle indicated by the set of radial lines just below it, the free end of the rocking arm 8 and the plunger 5 will be moved upwards for a way corresponding to the distance f , and a corresponding amount of fuel will now be injected into the cylinder. The distance f indicates, and corresponds to, the longest effective delivery stroke of the pump. While the injection is taking place, the regulating screw 13 is being lifted off the valve stem 10' by the lever or arm 14, that is to say, by the guide-member 4, the lever or arm 17, the rod 16, and said lever or arm 14, and when the delivery stroke has been finished, the suction stroke commences immediately thereafter, the plunger 5 moving now downwards for a length of way corresponding to the sum of the distances f plus r . While the distance or way f is being covered, the suction valve remains closed under the comparatively strong pressure of the spring 14, but while the distance or way r is being covered, the suction valve is opened by the finally greater pressure of the spring 6, this pressure being transmitted to the valve 10 by the parts 4, 17, 16, 14, 13, and 10'. The pump-chamber 1' is now again filled up with the liquid fuel, and this phase being finished, when the plunger 5 has made its entire suction stroke f plus r , the plunger moves now again upwards and forces another amount of the liquid into the cylinder, as already described, but while the path r is being covered the suction valve remains open so that a corresponding amount of the fuel is forced back around said valve. Then this latter is closed (position shown in Figure 1) and only now the actual injection takes place.

If, in order to reduce the amount of fuel to be injected, the slide 24 and the arm 8 are shifted to the right, the operating end of the arm 8 remains always in contact with the guide-member 4 and with the cam owing to the appropriate shape of the profile of the latter, without any shifting of the member 4.

The effective delivery stroke is reduced and, thus, the injection time is diminished corresponding to the shifting of the parts 24 and 8 to the right, whereas the time of commencement of the injection remains the same it was. If the parts 24 and 8 are shifted to the right for a length of way cor-

responding to the path a (see the little additional representation lefthand from the lower part of Figure 1), that is to say, corresponding to the stopping position, the effective quantity delivered is reduced to zero; the suction valve 10 is then open during the whole delivery stroke and is closed only in the upper dead centre of the plunger.

The above-mentioned little diagrammatical representation at the left of the lower part of Figure 1 shows the dependency of the effective pressure-stroke portion f , as well as of the return-flow stroke-portion r , upon the shifting of the parts 24 and 8.

In lieu of a rocker arm such as 8—which, for the sake of simplicity, has been illustrated without a piston—a bell-crank lever might be used, and the position of the fulcrum thereof could be altered, for instance by means of an eccentric, in such a manner that, on one side, said lever could slide on the suitably shaped cam without, on the other side, shifting the plunger.

While in the example illustrated in Figure 1 the fuel-valve 10 is operated by the intermediary of levers and rods, as shown and described, another example is shown in Figure 2 where said valve is controlled by the plunger 5; it is devised to form a so-called drag-valve, being provided with a downwardly extending U-shaped member 10^a which is coupled with the plunger 5 by an extension 5^a thereof and a head 5^b of this extension. The upper end of the spring 11 bears against said member 10^a. The valve is, thus, opened by the parts 5 5^a 5^b and closed by the spring 11. The position of the arrangement and combination of parts shown in Figure 2 (excepting the shaft and the cam) is the standstill position; the position of the shaft and the cam is the same as in Figure 1.

Concerning the manner of operation there is no material difference with respect to Figure 1, except the feature that owing to the direct control by means of the plunger the return-flow stroke-portion r is transmitted to the suction-valve 10 without any diminution.

In order to provide for the possibility to adjust the point of the time of ignition, the plunger 5 is, in Figure 2, not made integral with the guide-member 4, as in Figure 1, but forms a separate part which is screwed into the member 4. By turning the plunger in one or the other direction the moment of closing of the valve 10 can be so adjusted that the fuel-injection commences just in the point of time intended.

I claim:

1. A fuel injecting device of the character described, comprising a casing, a plunger and a guide member therefor, a cam mount-

ed beneath said guide member, a slide mounted for movement at right angles to said plunger, a regulating arm hinged at one end to said slide with its free end interposed between said guide member and cam, a swingingly-mounted arm loosely engaged in said slide, a suction valve movable in line with the plunger, and means operably connected with said guide and valve for actuating the latter.

2. A fuel injecting device of the character described, comprising a casing, a plunger and a guide member therefor, a cam mounted beneath said guide member, a slide

15 mounted for movement at right angles to said plunger, a regulating arm hinged at one end to said slide with its free end inter-

posed between said guide member and cam, a swingingly-mounted arm loosely engaged

20 in said slide, a suction valve movable in line with the plunger, and means operably connected with said guide and valve for actuating the latter, there being a chamber between the plunger and valve seat with a channel lead-

25 ing from the upper end of said chamber, and a valve controlling the flow of fuel from

said channel.

3. A fuel injecting device of the character described, comprising a casing, a plunger and a guide member therefor, a cam mounted beneath said guide member, a slide

15 mounted for movement at right angles to said plunger, a regulating arm hinged at one end to said slide with its free end inter-

posed between said guide member and cam, a swingingly-mounted arm loosely engaged

20 in said slide, a suction valve movable in line with the plunger, and means operably connected with said guide and valve for actuating the latter, there being a chamber between the plunger and valve seat with a channel leading from the upper end of said

25 chamber.

4. A fuel injecting device of the character described, comprising a casing, a plunger and a guide member therefor, a cam mounted beneath said guide member, a slide

15 mounted for movement at right angles to said plunger, a regulating arm hinged at one end to said slide with its free end inter-

posed between said guide member and cam, a swingingly-mounted arm loosely engaged

20 in said slide, a suction valve movable in line with the plunger, and spring means for closing said valve during the early upward

25 movement of the plunger.

In testimony whereof I hereunto affix my signature.

ERNST FREY.
